(57) **CLAIM**

I claim the ornamental design for a brush with neck, as shown and described.

DESCRIPTION

FIG. 1 is a top perspective view of the claimed design.

FIG. 2 is a first side elevation view thereof.

FIG. 3 is a second side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a detail front bottom perspective view of a ring thereof.

Those features shown in broken lines form no part of the claimed design.
